APPARATUS FOR FORMING CONCRETE PILES

Leonidas Lyroudias, Apartado Aereo 5878,
Bogota, Colombia

Filed Dec. 13, 1954, Ser. No. 474,921

2 Claims. (Cl. 61—63)

This invention relates to apparatus for forming concrete piles, and has as one of its primary objects the provision of such means for constructing concrete piles of any given diameter and of any desired length.

Another object of this invention is to provide means for constructing concrete pile foundations in the ground wherein as the piles are being constructed the operator may determine the actual carrying or supporting force thereof with a greater accuracy than is heretofore made possible.

A further object of this invention is to provide apparatus for constructing concrete piles with a relatively small and light weight device wherein the piles may be erected rapidly thereby saving both time and money.

A still further object of this invention is to provide apparatus means which enables the construction of concrete pile foundations without the use of reinforcing iron or steel.

This invention has, as another object, the provision of apparatus means for constructing concrete piles which are relatively inexpensive to manufacture, non-complex in operation, and durable in use.

Other and further objects and advantages of this invention will become more evident from a consideration of the following specification when read in conjunction with the annexed drawings, in which:

Figure 1 is a side elevational view of the apparatus for constructing concrete pile foundations in accordance with this invention, and showing the extractor apparatus in extended position.

Figure 2 is a medial longitudinal cross-sectional view, partly in elevation, of the apparatus shown in Figure 1, and illustrating the position of the tube extraction jaws in their respective non-gripping relation.

Figure 3 is a top plan view of the apparatus shown in Figure 2, showing the position of the extraction jaws when moved to their respective operable positions.

Figure 4 is an end elevational view of the tube extracting apparatus taken on the vertical plane of line 4—4 of Figure 3, looking in the direction of the arrows.

Figure 5 is a cross-sectional view, partly in elevation, taken on the vertical plane of line 5—5 of Figure 3, looking in the direction of the arrows.

Figure 6 is a fragmentary detail cross-sectional view illustrating the extractor gripping means.

Figure 7 is a vertical cross-sectional view of the concrete ejection apparatus.

Figure 8 is a cross-sectional view taken on the horizontal plane of line 8—8 of Figure 7, looking in the direction of the arrows.

Figure 9 is a cross-sectional view taken on the horizontal plane of line 9—9 of Figure 7, looking in the direction of the arrows.

Figure 10 is a cross-sectional view taken on the horizontal plane of line 10—10 of Figure 7, looking in the direction of the arrows.

Figure 11 is an end elevational view of the extrac-

2

tion apparatus taken on the horizontal plane of line 11—11 of Figure 7, looking in the direction of the arrows.

Figure 12 is a vertical cross-sectional view of the extracting device illustrating its working positions.

Figures 13 to 18, inclusive, illustrate the successive steps which are employed in utilizing the pile construction apparatus.

Referring now more specifically to the drawings, reference numeral 50 designates, in general, a concrete pile foundation constructing device constructed in accordance with the teachings of the present invention. The device 50 comprises a relatively rigid, substantially rectangular base member 51, formed of metal or other desired materials, and having an aperture 52 extending transversely therethrough adjacent one of its ends.

A pair of hydraulically operated jacks, designated in general by reference numeral 54, are mounted and secured on the base 51 by conventional means.

The jacks 54 are of identical construction and comprise a hollow cylindrical side wall 56 having telescoped therein (see Figure 1) a first substantially hollow tubular element 58, a second substantially hollow tubular element 60, and a third substantially hollow tubular element 62 closed at the upper end thereof.

The upper ends of the elements 62 terminate in an end portion 64 having an aperture 66 formed therein and extending substantially perpendicular to the longitudinal axis of the element 62.

A pair of links 68 are disposed on opposite sides of the end portion 64 and have their respective lower ends pivotally connected thereto by the pivot pin or axle 70, the pivot pin 70 extending transversely through the aperture 66.

The other ends of the links 68 are pivotally connected at 72 on opposite sides of and at one end 74 of a lever 76.

The other end of the lever 76 is secured, as by welding, to one side of an arcuate extractor jaw 78. The jaw 78 is provided with reinforcing upper and lower plates 80, 82 which are also secured to the lever 76 as by welding.

Referring now more specifically to Figures 2 and 3, it is seen that one end of a bell crank lever 84 is fixedly secured to the opposite ends of the reinforcing plates 80, 82, and the other, or lower end thereof is pivotally mounted at 86 between a pair of bearing plates 88 and 90.

The bearing plates are welded to a horizontally disposed support member 92 having a central aperture 94 formed therein. The plate 92 is connected with one end of a pair of angle members 96, the other end thereof being fixedly secured to the element 60 and are positioned on opposite sides of the element 62.

A conventional hydraulic fluid pump is disposed within a casing 98 and connects with the jacks 54 through the conduits 100 and 102.

Reference numeral 104 designates an elongated substantially hollow tubular pipe, the function of which will be set forth in detail below. As is seen in the drawings, the pipe 104 is adapted to be positioned between the jaws 78 and is adapted to be tightly gripped thereby. This operation takes place in the following manner.

Assuming that the pump within the housing 98 is supplying hydraulic fluid under pressure to the hydraulic jacks 54, the force thereof exerted on the element 62 causes the same to move vertically upwardly. This action causes the links 68 to move upwardly and pivot into the dotted line position shown in Figure 2.

As the links move upwardly, the bell crank levers 84 are pivoted about their axes at 86 causing the jaw members 78 to move inwardly and engage tightly against the hollow tubular pipe 104.

As shown in Figure 6, the jaws are provided with a serrated gripping surface 106 with the serrations being inclined vertically upwardly.

Thereafter, the element 60 moves vertically upwardly

and in so doing carries the hollow tubular member 104 upwardly therewith. The upward movement continues until the hydraulic jacks 54 have reached their maximum point of expansion.

The tube 104 has disposed therein a diametrically extending substantially rectangular spacer plate 200 which has its opposite ends fixedly secured thereto as by welding. As seen in Figures 7 and 8, the spacer plate 200 has welded to its upper and lower sides a plurality of laterally spaced ribs 202, and an elongated cylindrical open ended sleeve member 204 is rigidly secured to the outer ends of the ribs 202. The opposite ends of the sleeve 204 receive the respective base elements 206, 208 of a pair of oppositely disposed hydraulic jacks 210, 212. The base element 206 has telescopically mounted therein the telescoping elements 214, 216 and 218, and the base element 208 is provided with telescoping elements 220 and 222.

The hydraulic jacks 210 and 212 are connected with the pump disposed in the housing 98 through a flexible hose carrying two conduits (not shown), one for each of the jacks.

An inverted U-shaped spider 226 extends diametrically across the tubular member 104 and includes a pair of depending confronting spaced apart parallel arms 228, 230 which are positioned within and closely adjacent the inner surface of the tubular member 104. The lower ends of the arms 228, 230 are welded to an annular piston member 232 having a valve seat 234 at the center thereof. The annular member 232, being secured to the arms 228, 230 is fixed to the spider 226 and will reciprocate therewith. The spider 226 is fixedly secured to the lower end of the telescopic element 220 of the jack 212.

The annular member 232 is provided with a plurality of vertically spaced circular grooves 235, 236 with the lowermost one thereof having the greatest diameter, and the grooves are positioned in co-axial alignment with the valve seat 234.

A valve member 238 is fixedly secured to the lower end of the telescopic element 222 of the jack 212, and is constructed with an angularly inclined face 240 adapted to engage tightly the valve seat 234. A pair of substantially solid cylindrical members 242, 244 depend from the lower end of the valve 238 and the member 244 terminates in an end portion 246 having an inverted frusto-conical configuration.

A pair of diametrically opposed lugs 248, 250 are integrally formed with the valve 238 and each has secured thereto one end of an elongated rod 252, 254, respectively. The rods 252, 254 connect at their other respective ends with a cross-shaft 256 extending horizontally through the telescoping member 218 of the jack 212 adjacent its upper end.

With the interconnection of the piston member 232, valve member 238 and the jacks 210, 212, operation of the jack 212 is effective to first move the valve 238 against the piston member 232 and afterwards to move the piston member 232 in the pipe 104. The jack 210 is compressed by the jack 212 through the rods 252, 254 on operation of the jack 212. The jack 210 serves to compress the jack 212 on operation of the jack 210 to return the piston member 232 and valve 238 to normal position.

A cylindrical shield 258 surrounds the telescoping member 218 and has an integrally constructed conical cap 260 which bears on the upper end of the telescoping member 218.

In operation, the extractor device 50 is placed at the desired location for forming a concrete pile, the jacks 54 thereof being collapsed and the jaws 78 in their open position, as shown in full lines in Figure 2. The tubular member 104, the jacks 210 and 212, and the elements associated therewith are in the illustrated full line position of Figure 7, and it should be noticed that the valve 238 is in its open position. The tubular member 104 is now inserted in the extractor 50 between the jaws 78 and extends vertically from the ground.

Concrete 300 is then poured into the open upper end of the tubular member 104, and passes through the open valve seat 234 into the lower end of the tubular member 104. But care must be exercised that the volume of the concrete 300A does not exceed the volume of the space between the annular member 232 and the lower end of the tubular member 104 (see Figure 13). Thereafter, the jack 212 is placed into operation to initially effect downward movement of the telescoping element 222 causing the valve 238 to close against its seat 234. The jack 212 continues to operate and the telescoping member 220 moves downwardly to effect an initial compression of the concrete 300A (see Figure 14), and simultaneously therewith, the exerted pressure drives out all foreign materials which may have been present in the lower end of the tube 104.

A driver 302 now engages and moves the upper end of the tubular member 104 downwardly through the ground carrying with it the compressed concrete 300A, as shown in Figure 15. As the tubular member 104 descends, the resistance of each strata of the earth it passes through may be read from a manometer 304 connected in the hydraulic system of the jack 212. Should additional information be required, the geotechnic coefficient of the penetrated ground may be read from the manometer 306 connected in the hydraulic system of the jacks 54.

The driver 302 continues to operate until the desired resistance for the pile is found, naturally this resistance will be inferior to the final resistance since the concrete is still fresh.

The jack 210 is now actuated to restore the jack 212 to the full line position of Figure 7 and additional concrete 300 is poured into the tubular member 104. Jack 210 is now relieved of pressure and pressure is placed on the jack 212 to cause the concrete 300A to be ejected from the bottom of the tube.

The above described operations continue until a tightly packed mass of concrete 300B (see Figure 16) of a known volume is obtained.

In the described operation, the conical member 246 and the annular member 232 should never reach the end of the tubular member 104 so that the member always has a small layer of concrete therein to prevent the seepage of water therein and to avoid a severance of the pile at the base of the tubular member 104.

When the desired mass 300B of concrete has been obtained, the jack 212 is returned to its full line position of Figure 9 and more fresh cement is poured into the tubular member 104. The new cement is now placed under pressure by the jack 212 and simultaneously the jacks 54 of the extractor are placed into operation. The movement of the jacks 54 and 212 are synchronized so that the longitudinal movement of the tubular member 104 upwardly is less than the downward movement of the annular member 232 whereby a cement neck 300C (Figure 17) is formed.

The above described cycles of operation are sequentially repeated until the desired pile has been obtained, and the tube 104 is then withdrawn completely from the ground (see Figure 18).

To assist in breaking the suction under the valve 238, the annular member has been provided with the grooves 235 and 236.

It will be understood that as the jack 212 is extended during the operating cycle, the jack 210 retracts, and vice versa.

Having described and illustrated one embodiment of this invention in detail, it will be understood that the same is offered merely by way of example, and that the invention is to be limited only by the scope of the appended claims.

What is claimed is:

1. A device for constructing concrete piles in situ comprising an elongated upright pipe having the opposite

ends thereof open, a plate fixed transversely of said pipe intermediate the opposite ends thereof, an upper hydraulic jack base fixed to said plate to extend upwardly therefrom in axial relation to said pipe, a lower hydraulic jack base fixed to said plate to extend downwardly therefrom in axial relation to said pipe, a piston slidably mounted in said pipe below said plate and said hydraulic jack bases, a valve seat formed in said piston, a telescopic element mounted for reciprocation in said lower hydraulic jack base, means securing said piston to the lower end of said telescopic element with said piston spaced substantially below said telescopic element, a second telescopic element mounted for reciprocation in said first telescopic element, a valve carried by the lower end of said second telescopic element for cooperative engagement with said valve seat, a plurality of telescopic elements mounted for reciprocation in said upper said hydraulic jack base, opposed lugs on said valves, rigid rods secured at their lower ends to said lugs, a cross shaft secured to the uppermost of said telescopic elements, said rigid rods being secured at their upper ends to said cross shaft, thus connecting said valve to the uppermost of said plurality of telescopic elements whereby on supplying hydraulic pressure to said lower hydraulic jack base initially said valve is moved into closed position against said valve seat and successively said piston is moved in said pipe away from said plate and on supplying hy-

draulic pressure to said upper hydraulic jack base, said valve is moved away from said valve seat and said piston is moved axially in said pipe toward said plate.

2. A device as claimed in claim 1 wherein the means securing said piston to said first named telescopic element includes an inverted U-shaped spider fixed centrally to said first named telescopic element and having the opposite ends thereof fixed to said piston.
